UNITED STATES PATENT OFFICE.

JOHN ROBERTSON, OF BROOKLYN, ASSIGNOR TO ROTHE & LIPS, OF NEW YORK, N. Y.

APPARATUS FOR COVERING TELEGRAPH-CABLES.

SPECIFICATION forming part of Letters Patent No. 275,859, dated April 17, 1883.

Application filed April 8, 1882. (Model.)

To all whom it may concern:

Be it known that I, JOHN ROBERTSON, of Brooklyn, in the county of Kings and State of New York, have invented a new and Improved 5 Apparatus for Covering Telegraph-Cables, of which the following is a specification.

Figure 1 is a vertical cross-section of the improved machine for covering telegraph-cables. Fig. 2 is a vertical longitudinal section 10 of the lead-chamber; and Fig. 3, a top view, partly in section, of the apparatus. Figs. 2 and 3 are drawn on the same scale—that is, larger than the scale on which Fig. 1 is drawn.

The object of this invention is to produce a 15 convenient machine for covering telegraph-cables with lead, and also for applying an intermediate coating of paraffine, or the like, between the lead and the cable.

The invention consists in a new construction 20 of apparatus for ejecting the lead from a chamber and causing it to adhere to the cable, and also in the new combination of parts that have reference to the application of the paraffine, and to the cooling of the paraffine and 25 to the cooling of the lead on the finished cable.

The cable A, which is to be covered, is first drawn from a suitable reel through a tank or trough, B, containing paraffine or its equivalent, which trough is directly or by tubular 30 extension joined to the lead-chamber C. The cable A, passing through the paraffine in this trough, is covered with it to the proper extent, the paraffine being kept in a liquid or nearly liquid condition by means of steam or hot 35 water admitted into the hollow walls *a* of the trough B, the said trough being practically surrounded by a steam-jacket at the sides, outer end, and bottom. The lead-chamber C is a cylinder having its ends open, as shown 40 in Fig. 2, and contains a plunger D, axially aligned with it at each end, the two plungers being intended to eject the lead from the chamber, and being connected with suitable mechanism—such as hydraulic power, or the like— 45 for moving them toward the center of the chamber C. The chamber C is surrounded at or near its ends, and, if desired, also in the middle by a shell, E, which forms a steam-chamber, *b*, preferably of spiral form, as shown 50 in Fig. 2—that is to say, the outer circumfer-

ence of the chamber C is cut or shaped to produce spiral grooves, which are inclosed in the shell E, to which steam is admitted by the pipe F, and from which steam escapes by the pipe G. By this means the lead, in the 55 chamber C is kept warm, and the heat of the steam is fully utilized during its passage through the spiral grooves. It enters hot at the pipe F, and leaves the steam-jacket, in a practically chilled condition by the pipe G. 60 The chamber C is traversed at its center by the guide mechanism for the cable and discharged lead. This mechanism is more clearly shown in Fig. 3. It consists of the core H and of the die I. The core H is tubular and has a 65 tapering inner end. At its outer end it has an outwardly-projecting flange, *d*, which bears on a shoulder, *e*, that is formed in the corresponding radial bore of the chamber C. A hollow nut, J, is screwed into said bore and 70 bears against the outer end of the core H. The die I is also tubular, having a larger bore than the inner end of the core H, and is set into a recess or depression which is formed in the chamber C on the side opposite to that through 75 which the core is inserted. This depression is marked *f*, and serves to support the die I in its position. By unscrewing the nut J the core H can be readily taken out, and thereupon, also, the die I through the opening that was 80 formerly partly filled by the core H, and another die and core may be placed into the chamber C in lieu of those removed, so that thus the apparatus is adapted to cover cables of different sizes or cover the cables with different thicknesses of lead, as may be desired, different cores and dies being used for the different kinds of cable or covering to be passed through the machine. The inner side of the core H has a screw-thread cut into it, as 85 shown at *g*, to facilitate its removal—that is to say, after the nut J is removed a threaded rod is screwed into this thread *g*, and by its movement the core H is readily pulled out.

The operation of the apparatus is as follows: 95 The cable A, having been covered with paraffine, is passed through the tubular nut J and through the hollow core H, and thence through the die I, and out of the chamber C at *h*. The perforation of the die I is somewhat larger 100

than that of the core H. The plungers D, being gradually moved toward one another, squeeze the lead out of the chamber C, the only outlet for it being through the die I, around the cable; and thus it is that a tubular lead covering is applied to the cable around the same, of such thickness as is allowed by the bore of the die I, the ejection of the lead serving also to feed the cable in the direction of the arrows and in harmony with the speed of the escaping lead.

In Fig. 3 the letter *i* represents the cable before it is covered with paraffine, the letter *j* the cable covered with paraffine, and the letter *l* the cable covered with lead.

It will be seen that by having the two plungers working from opposite sides the lead is caused to escape from the chamber C in an equal stream, while where there is only one plunger the tendency is that it will escape more on one side of the cable than on the other, and produce an unequal covering. The core H should be so perforated that at the point where the cable leaves it it will hug it, and thus prevent the lead from escaping back-

ward through the core, whereas the die I leaves a sufficient opening for the discharge of the lead in the manner stated.

The cable thus covered with lead is finally discharged from the chamber C, and then 30 passed through a water-tank, L, where it is cooled, and finally wound on a reel, M.

I do not claim, broadly, surrounding any lead-chamber with a steam-jacket.

I claim—

1. In apparatus for covering cables with lead, the removable core H, made with inner thread, *g*, as and for the purpose described.
2. The cylinder C, having radially-placed cavity *f* on one side of its axis, and aperture 40 with shoulder *e* on opposite side of same, in combination with the die I and with the tubular core H, provided with flange *d* and with the nut J, substantially as and for the purpose specified.

JOHN ROBERTSON.
